UNITED STATES PATENT OFFICE.

JOHN J. VOGLER, OF DOUGLASTON, NEW YORK, ASSIGNOR TO ALFRED H. SMITH CO.,
OF NEW YORK, N. Y., A CORPORATION OF NEW YORK.

DISPLAY STAND.

Application filed January 11, 1924. Serial No. 685,539.

This invention relates to certain improvements in display stands, being particularly designed for displaying tooth brushes and similar articles having handles.

5 It is the especial object of the invention to provide a display stand of improved design which shall make an attractive appearance on a counter or in a show window in which the tooth brushes or similar articles, provided with handles, may be displayed in an erect position, the stand being designed so that handles varying in size may be positioned as desired in the stand.

10 It is a further object of the invention to provide such a stand in which the articles to be displayed may be readily put in position in the stand and removed therefrom.

15 With these and other objects not specifically referred to, the invention consists in certain novel parts, arrangements and combinations which will be described in connection with the accompanying drawings, and the novel features pointed out in the claim hereunto appended.

20 In these drawings—

Figure 1 is a perspective view of the improved stand.

Figure 2 is a section taken on line 2—2 of Fig. 1, certain of the brushes being omitted.

25 Figure 3 is a vertical sectional view taken on line 3—3 of Fig. 2.

Figure 4 is a partially broken away view of the bottom of the stand.

30 Referring now to these drawings, the improved stand will include a base 1, which may be of any suitable character, being in the present instance shown as rectangular in shape having two long sides 2 and two short sides 3. This base is arranged to hold the articles, such as toothbrushes in upright position, the brushes being held with the brush part at the top, and is provided with recesses to receive the handles of the brush. These tooth brush handles are apt to vary somewhat in size so that means are provided for accommodating handles which vary somewhat in size, the handle receiving recesses being provided or formed with handle receiving surfaces which will yield to permit this. While the specific construction for effecting this may be somewhat varied, as shown the base is provided with a row of recesses 4 with intervening webs 5, these recesses being provided in any desired number. 35 The walls of these recesses are provided

with resilient or spring means which will yield to receive the brush handles, and in the particular embodiment of the invention illustrated, these recesses will be provided with plugs or blocks of rubber or similar yielding or springy material, indicated by the numeral 6. These plugs may be secured in the recesses in any suitable manner, but in the particular construction illustrated they will preferably be secured therein so as to be held against accidental withdrawal from the recesses when the brush handle is removed from the plug. This is simply effected by providing the plugs with a flange 60 which takes under a shoulder 8 formed by cutting away the base underneath the same, the plugs being inserted in the recesses from the underside of the base. The plugs are held in position and kept from pulling out of the recesses in any suitable manner, as by 65 a strip of veneer or the like, indicated at 9.

70 These handle receiving plugs are provided with sockets, indicated by the numeral 10, and these sockets, in the best constructions are downwardly tapered, as indicated 75 at 11 in Fig. 2. These sockets are, furthermore, shaped approximately like the brush handle they are to receive, being, as in the present instance, somewhat elongated to receive the handles 12 of the brushes, and these 80 sockets will extend across the base as shown so that the heads of the brushes will face sideways with respect to the long dimension of the case, thus displaying the brushes to the best advantage, and providing a construction by which the brushes can only be placed in their correct position by the attendant in filling the case.

85 The display stand may, if desired, be provided with a casing which surrounds the brushes, and this casing will preferably be provided with an opening so as to permit the ready removal of the brushes therefrom. While this case may be of various forms, as shown it comprises a top 13, a front wall 14 and end walls 15, which may be of any suitable material as glass, the back of the casing 16 being left open through which the brushes may be inserted in position and removed 90 from the casing.

95 With the stand shown and described, brushes and similar articles having handles which vary considerably in cross section may be accommodated in the case and may be secured therein so as to stand firmly erect, and 100 105 110

at the same time an attractive display of the articles is made, and provides a construction which is simple and, therefore, cheap to make.

- 5 While the invention has been shown in its preferred form, it will be understood that the size, shape and material of the sockets by which the brush handles are held may be varied to some extent, as also may be the manner in which they are secured in the base, without departing from the invention as defined in the appended claim.

What I claim is:

A display stand for tooth brushes and

similar articles having handles, comprising 15 a base member having a recess provided with a shoulder adjacent the bottom thereof, a rubber plug seated in said recess, a flange on said plug arranged to overlie said shoulder, said plug having an opening there- 20 in arranged to receive the handle of the article, and a strip arranged to be secured to bottom of the base member to prevent displacement of said plug.

In testimony whereof, I have hereunto set 25 my hand.

JOHN J. VOGLER.
